Primary Examiner — Cathron C Brooks*Assistant Examiner* — Samantha Q Lawrence(74) *Attorney, Agent, or Firm* — Ware, Fressola, Maguire & Barber LLP(57) **CLAIM**

We claim the ornamental design for a catheter with cutting element, as shown and described.

DESCRIPTION

FIG. 1 is a left side view of a catheter with cutting element; FIG. 2 is a right side view of the catheter with the cutting element;

FIG. 3 is a front view of the catheter with the cutting element;

FIG. 4 is a top plan view of the catheter with the cutting element; and,

FIG. 5 is a bottom plan view of the catheter with the cutting element.

The break lines indicate a symbolic break in length. The appearance of any portion of the article between the break lines forms no part of the claimed design.
